UNITED STATES PATENT OFFICE

2,584,927

BASE CONSTRUCTION FOR DISPENSERS

Frank E. Sanborn, Chicago, Ill., assignor to The Dole Valve Company, Chicago, Ill., a corporation of Illinois

Application November 22, 1946, Serial No. 711,489

11 Claims. (Cl. 248—360)

1

The present invention relates generally to base construction for dispensers and more particularly to the construction of a base for supporting a drink dispenser on a soda fountain bar in a manner to leave the counter free and of the same type as shown in Tweed Patent No. 2,157,154.

Drink dispensers have been mounted or supported on soda fountain bars by means of a base member which occupies the space of several syrup jars, the base having means for spanning the distance between the ledge and wall constituting the jar support and which base is provided with means for accommodating it to bars in which the jar supports may vary in width and also in which the jar supports may vary in angularity with respect to the horizontal.

A fountain bar of the usual type has a counter for general use of the customers, back of the counter and along it, for a portion of the length of the counter, means are provided for supporting a plurality of syrup jars in a row, the jars tilted to permit ready access by the counter man. Usually such a fountain bar has a ledge or shoulder for engagement by rear flanges of the syrup jars and spaced from it a distance to receive the jars is a rail or wall parallel to the ledge, with the upper margin of the wall below the horizontal plane of the ledge so that the jars may be supported in inclined or tilted position with respect to the horizontal.

The base construction of the present invention includes one part which has means resting on the ledge and on the wall, spanning the distance between them, in inclined position. Another part of the base, which directly supports the dispenser, is adjustably supported on the first mentioned part to be positioned with its upper margin in a horizontal plane. The spanning means are adjustable to accommodate them to whatever the width of the jar space may be in a soda fountain bar to be equipped with a dispenser.

It is therefore an object of the present invention to provide a dispenser base which may be readily fitted to a fountain bar regardless of the space between the ledge and wall of the syrup jar compartment and regardless of the difference in height between the ledge and wall, and which when fitted will be firmly secured for supporting a dispenser with the dispenser in erect position.

Another object of the present invention is to provide a base construction with means for positively clamping the base to the ledge and wall of a syrup jar compartment.

A further object of the present invention is to provide, in a dispenser base, endwise adjustable

parts for spacing the distance between the ledge and wall of a syrup jar compartment.

The invention has for an additional object the provision of slotted links and cooperating fastening devices for angularly adjusting the parts of the base to fix the upper margin of the upper portion in a horizontal plane.

Another and yet further object of the present invention is to provide a dispenser base with means for clamping the base to the edge of a soda fountain bar by a lever of the third class.

A still further object of the present invention is to provide a base for a dispenser to support the dispenser in a soda fountain bar, in which the front plate of the base is secured in place by snap-on action and which plate carries a support for a glass or a cup.

Another and yet further object of the present invention is to provide, in a dispenser base, means for spanning the distance between the ledge and wall of a syrup jar compartment of a soda fountain bar, which means include channel members endwise adjustable, one member for resting on the ledge and the other member for resting on the wall.

The invention has for an additional object the provision, in a base for supporting a drink dispenser on a soda fountain bar, of means for spanning the distance between the ledge and wall of a syrup jar compartment, which means include endwise movable members, means for securing the members in adjusted relationship, and positive clamping means on the outer ends of the members to engage respectively the ledge and wall of the jar compartment.

The above, other and further objects of the present invention will be apparent from the following description and accompanying drawings.

An embodiment of the present invention is illustrated in the accompanying drawings and the views thereof are as follows:

Figure 1 is a vertical sectional view through the syrup jar compartment of a soda fountain bar, with parts in elevation, and showing in side elevation a base of the present invention fixed in place, and showing a fragmental portion of a dispenser, in elevation, on the base.

Figure 2 is an enlarged sectional view taken in the plane of line II—II of Figure 1.

Figure 3 is a top plan view of the base, and

Figure 4 is a vertical sectional view, with some parts in elevation, taken in the plane of line IV—IV of Figure 3.

As shown on the drawings:

Referring to Figure 1, 10 designates general-

ly a soda fountain bar, having a front wall 11, a counter 12 and a syrup jar compartment 13. In order to support a plurality of syrup jars in the compartment there is provided a ledge 14 along the rear margin of the counter 12, and a wall 15 laterally spaced from the ledge. It may be noted that the wall 15 is inclined to the right as shown in Figure 1, to conform to the inclination of the syrup jars when inserted in the compartment 13. It will be noted, also, that the top margin 16 of the wall 15 is below the ledge 14. The ledge 14 is shown as provided with an inclined surface 17 which lies in an inclined plane including the top surface 16 of the wall 15.

For convenience, the space between the ledge 14 and the wall 15 will herein sometimes be designated as the throat 18 of the syrup jar compartment 13.

Referring to Figure 3, A designates the skirt portion of the base of the present invention. The skirt portion A is illustrated as a casting having side walls 19 and 20 and a rear wall 21. The lower portion of the rear wall 21 is formed with a footing 22 which, when the base is in place on a soda fountain bar, rests on top of the counter 12 adjacent the ledge 14 and constitutes a support for the counter end of the base. A flange 23 is formed along the upper margin of the rear wall 21, as may be noted in Figures 3 and 4.

Generally speaking, the skirt A may in top plan be somewhat in the form of U-shape, although in the construction illustrated the side walls 19 and 20 converge towards the open end of the skirt. Between the side walls 19 and 20, and near the top thereof, is a cross brace 84, formed as an integral part of the side walls.

The side walls 19 and 20 are herein illustrated as having inwardly offset portions 24 and 25, respectively, the inner surfaces of which are parallel, as may be noted in Figure 3.

For spanning the space between the ledge 14 and the wall 15 bridge members are provided.

Referring to Figure 4 a bridge member comprises two endwise adjustable channel members designated generally as B and C.

There are two separate members B and one member C. A channel member B is formed with its side walls 26 and 27 projecting upwardly, which walls are of unequal height, the wall 27 being higher. It will be noted that the height of the side wall 26 varies in its length. The top margin of the side wall 26, at the left hand end of the member B, in Figure 4, tapers upwardly and then downwardly and then in a direction parallel to the web of the channel member B. The left hand end of the wall 27 tapers upwardly and horizontally and thence downwardly merging with the straight portion adjacent the right hand end of the channel member.

The channel or bridge member C, or sometimes herein mentioned as the hook member, is formed of sheet metal of U-shape in plan, with two marginal parallel channels 89 and 90 as the legs and an intermediate body portion including a hood 46. The channel 89 is entered in the channel of one of the members B with the channel 90 entered in the channel of the other member B, as may be noted in Figure 3.

The channels 89 and 90 have walls of equal height and are assembled within the troughs of the channel members B. Referring to Figure 3 it will be noted that the webs of the channels 89 and 90 are slotted lengthwise as at 28. The web 29 of a channel member B is provided with a

bolt hole 29a. A bolt 31 is entered through the slot 28 of a channel 89 or 90 and the hole in the web 29 of the channel member B. A nut 32 is threaded onto the bolt to tighten it when it is desired to fix the channel members B and C in relatively adjusted position.

In order to prevent a bolt 31 from turning, as its nut 32 is manipulated, a Z-shaped washer is provided on the bolt under its head with one flange 33 extending downwardly through the slot 28 in a channel 89 or 90 and its other flange 34 upstanding against the bolt head against one face thereof, as may be noted in Figures 3 and 4. The lengths of the channel members B and C are such as to span the widest throat 18 of any commercial soda fountain bar in use.

Referring to Figure 3 it will be noted that there are two bridge members B used in the base construction of the present invention.

For connecting the bridge members to the adjacent walls of the skirt A, in a manner for angular adjustment between the bridge member and the skirt member A the following construction is employed. To the higher wall 27 of each of the bridge members B three slotted links 35, 36 and 37 are pivoted. The link 35 is secured to the wall 27 by a pivot 38. The links 36 and 37 are connected to the wall 27 by a single pivot 39. It will be noted that the link 36 crosses the link 35. Projecting through suitable apertures in the offset portion 24 of the side wall 19 of the skirt A are bolts 40 and 41. The bolt 40 passes through the slots in the links 35 and 36, as shown in Figure 4 while the bolt 41 passes through the slot in the link 37. A washer 42 is applied about the bolt 40 while a similar washer 43 is applied about the bolt 41. A nut 44 is threaded onto the bolt 40 and a similar nut 45 is threaded onto the bolt 41.

As a clamp means for securing the outer end of the bridge member C to the wall 15 a hood member 46 formed as an integral part of the bridge member C has a downwardly and inwardly turned flange 47 to engage the outer surface of the wall 15. Inwardly of the wall 15 the hood member 46 has a flange 48 which is downturned and threaded to receive a bolt 49. The bolt carries on one end a swivel cup 50 for engagement against the inner surface of the wall 15, and at the other end a sliding pin 51 is arranged within an aperture in the end of the bolt to serve as a handle for rotating the bolt 49 to tighten or loosen the clamp with respect to the wall 15.

The illustrated means for clamping a bridge member B to the ledge 14 includes the following: welded or otherwise secured to the under surface of the web 29 of a bridge member B is a U-shaped clip 52 having registered apertures in its flanges through which a pin 53 passes.

A lever D is formed from sheet metal into substantially U-shape in section having a web 54 and side walls 55 and 56 which are laterally spaced from each other, as may be observed in Figure 2. The walls 55 and 56 are provided with a plurality of registering apertures 57 to receive a pin 58 for securing a foot member 59 to the lever. The pin 58 has a head 60 and its other end apertured to receive a cotter pin 61 for preventing displacement of the pin and the foot 70 when assembled in the lever.

The pin 53 has a head 62 and is held in place by a cotter pin 63.

In order to move the lever D with respect to the bridge member B the following means are employed: a pin 64 is entered in registering aper-

tures of walls 26 and 27 of the bridge member. Centrally of the pin there is a bore through it. A pin 65 is arranged in registering apertures 66 in the side walls 55 and 56 of the lever D. This pin has a threaded bore through it. A long screw 67, having a head 68, is introduced in the bore in the pin 64 and is threaded through the pin 65, thus the lever D is moved toward and away from the bridge member B about the pin 53 as a pivot, as the screw is rotated. The pins 64 and 65 rock in their apertures as the screw is manipulated, advanced or retracted, so that there is always a straight line of stress between the lever D and the bridge member B.

The open end of the skirt A is normally closed by a front plate 69 which is removable. Referring to Figures 3 and 4 lugs 70 and 71 are formed projecting from the inner surfaces of the side walls 19 and 20 respectively, near their upper and right hand corners. The end plate 69 is formed with side flanges 72 and 73 which fit against the end margins of the walls 19 and 20 of the skirt A and when in position is inclined as shown in Figure 4. The upper ends of the flanges 72 and 73 are notched to receive the lugs 70 and 71 when the plate is applied to the skirt.

Extending inwardly from the offset portions 24 and 25 of the side walls 19 and 20 are lugs 74 and 75, which lugs are short as may be noted in Figure 3. Between the lugs 74 and 75, and endwise spaced from each, is a bar 76 connected to the lugs by bridge pieces 77 and 78, which bridge pieces are triangular in side elevation with apertures at their apices. The front plate 69 is provided with headed tongues 79 and 80 to make snap engagement with the bridge pieces 77 and 78 respectively when the front plate 69 is applied to the skirt member A. The manner of retaining the plate member 69 in place may be readily observed in Figures 3 and 4.

Secured to the front plate 69 is a shelf or ledge 81 constituting a support for a glass or cup while the glass or cup is being filled from the dispenser. The shelf 81 is illustrated as having a vent 82 through which waste liquid may pass through an outlet 83, in the event any liquid spills out of the glass or cup while being filled.

Integral with the walls 19 and 20 of the skirt A, and near the upper margins thereof, is a cross-brace 84. At mid-length of the brace there is a horizontal hole 85 through it. In one side face of the brace is a vertical recess 86 with its center line at right angles to the hole axis. A hex nut 87 is seated in the recess with its threaded opening in register with the hole 85. A screw 88 is threaded into the nut 87. The screw 88 engages a depending plate on the bottom of the dispenser, when the dispenser is applied to the skirt A to fasten the dispenser to the skirt.

The manner of applying the base structure of the present invention to a soda fountain bar is as follows:

Having removed from the throat 18 of the syrup jar compartment a sufficient number of syrup jars, and with the front plate 69 removed, the screws 44 and 67 are manipulated so that the hood 46 may be applied over the wall 15 and levers D applied underneath the ledge 14, as may be noted in Figure 4. If the length of the bridge members comprising the channel members B and C be insufficient to span the throat 18, then the nuts 32 are loosened on the bolts 31 and the members B and C moved endwise to provide a sufficient length to support the base on the ledge and wall, whereupon the nuts 32 are tightened to

hold the members B and C against relative movement in the then adjusted relation. When the bridge members have been applied as mentioned, the screw 49 is manipulated to tighten the clamp against the wall 15 and the screws 67 then manipulated to swing the levers D in a direction to force the foot members 59 against the underside of the ledge 14 and thus clamp this end of the bridge member to the ledge. It will thus be observed that the bridge member is securely fastened to the ledge 14 and the wall 15. When the bridge members are securely clamped to the ledge 14 and wall 15, the nuts 44 and 45 are loosened so that relative adjustment may be made between the skirt member A and the bridge members to bring the upper margin of the skirt member into a horizontal plane. When the member has been so adjusted the nuts 44 and 45 are tightened thus securing the bridge members and the skirt member in a desired adjusted position.

So far in this description of the present invention but one of the bridge members B has been herein described. It is to be understood that the other bridge member B is identical in construction and operation therefore it is assumed a description of the companion bridge member is unnecessary.

After the base member has been secured to the fountain bar, in the manner described, the dispenser F is applied to the skirt member A. The dispenser has a lug to engage underneath the flange 23 of the rear wall 21 of the skirt member and also has a flange to contact the cross brace 84 and to be fastened thereto by the screw 89.

After the base has been mounted on the soda bar and the dispenser F secured to the base, then the front plate 69 is snapped in place.

The dispenser F has an outlet 95, Figure 1, through which liquid, under control of the valve not shown, may enter a glass on the shelf 81.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a soda fountain bar having syrup jar supporting means adjacent one edge of a counter and including two parallel laterally spaced members arranged to support a row of coaxially disposed syrup jars, the improvement of a drink dispenser supporting base adapted to be supported on said two spaced members, said base including bridge means spanning the space between said two members, and said bridge means having at each end adjustable clamping means for obtaining a selectively variable clamping purchase on said two parallel spaced members.

2. In a soda fountain bar having syrup jar supporting means back of and along the counter, said means including two parallel laterally spaced members between which the syrup jars are supported, a two-part drink dispenser supporting base supported on said two members, said base including an upper part and a lower part, said lower part comprising two separate and laterally spaced parallel channel members disposed with their flanges upstanding and a one-piece hook member having marginal channel portions slideable in the said two channel members with the flanges of said marginal channel portions downturned, the said two channel members and said

hook member having cooperating means for securing them in endwise adjustment, said hook member having a transversely elongated downturned hood for engagement over one of said two parallel jar supporting members and having means for clamping said hook member to said one of said two parallel jar supporting members, each of said two separate channel members having means for clamping it to the other of said two parallel jar supporting members, the upper part of said base having sidewalls outwardly of the outer flanges of the said two channel members, and the outer flanges of said two channel members and the side walls of the upper base part having cooperating means for adjusting the upper base part with respect to the lower base part to level the tops of the side walls of the upper base part.

3. A base of the character described for securing to the ledge and wall defining the throat of a syrup jar compartment of a soda fountain bar, comprising a U-shaped skirt, means spanning the space between the ledge and wall of said bar and having end clamps for engaging the ledge and wall to fasten said spanning means in place, slotted links and cooperating fastening means for adjustably securing the skirt to said spanning means so that the upper margin of the skirt is in a horizontal plane, and a snap on end plate for closing the open end of said skirt, said end plate carrying a support for a glass or cup.

4. A multi part base for supporting a drink dispenser on a soda fountain bar comprising an outer skirt having two side walls and a back wall and open at its front and bottom and constituting an upper part, two channel members having upwardly extending walls of unequal height disposed with the higher walls against the inner surface of the walls of said upper part, slotted links pivoted to said higher walls of said channel members, fastening devices secured to the walls of said upper part and extending through the link slots to fasten said channel members to said upper part in adjusted relation, other channel members endwise movable in said first channel member to vary the distance between the outer ends of said channel members, each of said first channel members having means for clamping similar ends of said channel members to a fountain ledge and each of said second channel members having means for clamping similar ends of said second channel members to a wall, and means for fastening said channel members together in adjusted endwise relation.

5. In a soda fountain bar having syrup jar supporting means comprising a ledge along the bar counter and a wall spaced from the ledge and parallel to it to define a space for the jars, the upper margin of said wall being below said ledge, bridge means for spanning the distance between said ledge and said wall comprising extension means including a channel member with its walls of unequal height extending upwardly from the channel web, a second channel member within the walls of the first member with the margins of the walls of the second channel member against the web of the first channel member, the web of the second channel member having an elongated slot in it and the web of the first channel member having a bolt hole in it, a bolt through said slot and hole, a nut on said bolt to tighten it to hold said members in desired adjusted position, a Z-shaped washer having one flange in the slot and the other flange against the bolt head to prevent turning of the bolt as the

nut is manipulated, slotted links pivoted to the higher wall of said first channel member, and a second part having fastening means in the slots of said links to relatively adjust said second part with respect to said first channel member and separately adjustable clamping means on each of said channel members to obtain a clamping purchase on the ledge and on the wall.

6. In a soda fountain bar having syrup jar supporting means comprising a ledge along the bar counter and a wall spaced from the ledge and parallel to it to define a space for the jars, the upper margin of said wall being below said ledge, bridge means for spanning the distance between said ledge and said wall comprising extension means including a channel member with its walls extending upwardly from the channel web, a second channel member within the walls of the first member with the margins of the walls of the second channel member against the web of the first channel member, the web of the second channel member having an elongated slot in it and the web of the first channel member having a bolt hole in it, a bolt through said slot and hole, a nut on said bolt to tighten it to hold said members in desired adjusted position, a Z-shaped washer having one flange in the slot and the other flange against the bolt head to prevent turning of the bolt as the nut is manipulated and clamping means on opposite ends of said bridge means to obtain a clamping purchase on said ledge and upon said wall.

7. In a mounting for attaching a dispenser to a soda fountain syrup jar support, upper and lower sections between the dispenser and support and means for adjustably clamping said sections together and for attaching them to said support, said means including an adjustable lever device detachably clamped with one side of the support, a clamp engaging the other side of the support, and elongated scissor-like slotted links interconnecting said sections and adjustable for relative movement of the sections.

8. In a mounting for attaching a dispenser to a soda fountain syrup jar support, upper and lower sections between the dispenser and support and means for adjustably clamping said sections together and for attaching them to said support, said means including an adjustable lever device detachably clamped with one side of the support, a clamp engaging the other side of the support, and elongated scissor-like slotted links interconnecting said sections and adjustable for relative movement of the sections, said lever device including screw means for tightening it in position between said support and said sections.

9. A base for supporting a dispenser unit over two spaced apart ledges comprising a U-shaped housing having upright wall defining a horizontal support surface receiving the dispenser, a member supported between said ledges, and adjustable means for connecting said member to said housing including cross arms pivotally mounted on said member having slots receiving bolts connected to the wall of said housing.

10. In a soda fountain bar of the type having two parallel laterally spaced members adjacent one edge of a soda fountain counter and between which syrup jars may be supported, the improvement of a drink dispenser supporting base adapted to be supported on said two spaced members, said base including adjustably extendible bridge means to span the space between said members, a first adjustable clamp having a variable clamping throat to receive one of said members on one end

of said bridge means and a second adjustable clamp having a variable throat to receive the other of said two members, whereby said adjustable clamps may obtain a selectively variable clamping purchase on said two members to place said supporting base in firm assembly therewith.

11. A base of the character described for securement to the ledge and wall defining the throat of a syrup jar compartment of a soda fountain bar, comprising a U-shaped skirt, extendible means spanning the space between the ledge and wall of said bar and having end clamps for engaging the ledge and wall to fasten said spanning means in place, slotted links and cooperating fastening means for adjustably securing the skirt to 15 said spanning means so that the upper margin of the skirt is in a horizontal plane, and a snap-on end plate for closing the open end of said skirt,

said end plate carrying a support for a glass or cup, and said extendible spanning means being selectively adjustable endwise, whereby different widths between a ledge and a wall may be accommodated.
